Carl B. Christensen, Fairfield, Conn., assignor to Ready
Tool Company, Stratford, Conn., a corporation of Connecticut

Application February 6, 1958, Serial No. 49,524

Term of patent 14 years

(Cl. D58—13)

Fig. 1 is a top plan view of a box for a machine tool center, showing my new design;

Fig. 2 is a side elevational view thereof;

Fig. 3 is a bottom plan view thereof;

Fig. 4 is an end elevational view thereof taken from the left of Fig. 1; and

Fig. 5 is an end elevational view thereof taken from the right of Fig. 1.

The broken lines shown in Fig. 1 of the drawing are for illustrative purposes only.

I claim:

The ornamental design for a box for a machine tool center, as shown and described.
